UNITED STATES PATENT OFFICE.

JULES H. VENON, OF NEW YORK, N. Y.

DESIGN FOR AN ORNAMENTATION FOR DISHES.

47,767.

Specification for Design. Patented Aug. 24, 1915.

Application filed May 12, 1915. Serial No. 27,721. Term of patent 7 years.

To all whom it may concern:

Be it known that I, JULES H. VENON, a citizen of the United States, and resident of the city, county, and State of New York, have invented a new, original, and ornamental Design for an Ornamentation for Dishes, of which the following is a specification, reference being had to the accompanying drawing, forming part thereof.

The figure of the drawing is a plan view of a dish showing my new design of ornamentation thereon.

The design comprises a series of concentric circles or gold lines, conforming in

shape to the outline of the dish, the outer being adjacent the edge of the dish. The inner circles or lines are interrupted by a series of groups of flowers and leaves symmetrically placed about the edge of the dish, each group comprising pink roses, yellow daisies and green leaves, symmetrically grouped, substantially as shown in the drawing.

I claim:

The ornamental design for an ornamentation for dishes, as shown and described.

JULES H. VENON.
